UNITED STATES PATENT OFFICE.

PAUL A. BANCEL, OF NUTLEY, AND JOHN F. KIRGAN, OF PHILLIPSBURG, NEW JERSEY,
ASSIGNORS TO INGERSOLL-RAND COMPANY, OF JERSEY CITY, NEW JERSEY, A COR-
PORATION OF NEW JERSEY.

JET AUGMENTER OR EJECTOR.

Application filed August 18, 1922. Serial No. 582,743.

To all whom it may concern:

Be it known that we, PAUL A. BANCEL and JOHN F. KIRGAN, both citizens of the United States, and residents of Nutley, county of Essex, State of New Jersey, and Phillipsburg, county of Warren, State of New Jersey, respectively, have invented a certain Jet Augmenter or Ejector, of which the following is a specification, accompanied by drawings.

This invention relates to jet augmenters or ejectors, more particularly for augmenting fluid pressure in any desired apparatus, such as a condenser, cooler or similar vessel, by means of fluid jets, in which the fluids are separated into a plurality of separate enveloping layers or strata, which later commingle.

The primary object of the invention is to simplify and improve the construction of the augmenter or ejector and to cause the steam to be emitted from the nozzle in the form of a hollow cylindrical jet or envelope, so that a large area is provided inside and outside of the jet or envelope of steam for the entrainment of the air and other vapors from the condenser.

A further object is to construct the ring nozzle and diffuser of few parts and of such shape that they effectively cooperate with each other to cause the steam to be emitted from the nozzle in the form of a cylindrical jet or envelope surrounding an inner envelope of air and vapor, the steam jet being itself surrounded by an outer envelope of air or vapor, and the inner envelope of air surrounding a core of cooling water which is forced through the center of the enveloping fluid strata.

Another object is to introduce the cooling water at a point in the diffuser body, and in a manner, which is most effective for cooling purposes and to obtain a certain condensing effect.

Further objects will later appear and to the ends set forth our invention consists in the features of construction and operation described in the following specification and illustrated in one of its preferred forms in the accompanying drawings, in which—

Figure 1 is a top plan view of the ejector, Figure 2 is a longitudinal sectional elevation of an ejector.

Referring to the drawings, the body por-

tion or diffuser A of the ejector is cast or otherwise constructed in one piece, and as shown is formed with the contracted throat B having the enlarged outlet C at one end of the body, preferably surrounded by the securing flange D which may be provided with securing apertures and fastening means (not shown), by means of which the ejector is secured in position on the desired apparatus with which it is to be used. The inlet E of the ejector, for air or other vapor, or both, is preferably formed in a straight tubular portion F of the inlet head G which forms part of the body and extends at an angle to the longitudinal axis of the ejector, in this instance the inlet E being shown at right angles to said axis and provided with the securing flange H.

A nozzle aperture J is provided at the end of the body portion adjacent to the inlet head G for the insertion of a nozzle body K in axial alignment with the throat B. It is important that the nozzle aperture J shall be concentric with the throat of the diffuser for good operation. The nozzle body K is provided with an externally screw threaded portion L which is adapted to cooperate with a screw threaded portion O of the nozzle aperture J for removably connecting the nozzle body K to the inlet head G. An offset portion P is preferably formed on the outer end of the nozzle body K to facilitate adjustment, and also to provide a connection between an inlet aperture Q in the nozzle body K and an exterior source of fluid supply (not shown) but which may be steam, by means of a pipe R. The nozzle flange S is adapted to bear against the head G and form a tight joint and the meeting surfaces of the flange S and head G are preferably machined so as to be true with each other and the parts are preferably constructed and adjusted with the outlet of the nozzle in proper position relative to the throat B, although the nozzle body K may be adjusted longitudinally in different positions if required by inserting a spacer in the form of a washer or packing material between the meeting surfaces of the flange S and the body A.

The nozzle body K is formed with an inner tubular extension T, an outer annular flange U, and an annular chamber V between the tubular extension T and flange U.

The tubular extension T projects slightly beyond the end of the flange U and the outer cylindrical wall of the extension T gradually decreases in diameter toward the outer end beginning at a point W just below the end of the flange U. An annular ring or cap X having a reduced diameter screw threaded portion Y is adapted to be threaded into the flange U which is provided with 10 internal screw threads Z for this purpose.

The ring X surrounds the end of the tubular extension T and the opening in the ring X is of slightly greater diameter than the widest portion W of the tubular extension T, so that an annular or ring passage a is formed between the flange U and tubular extension T, this ring passage a gradually increasing in volume beginning at the point W. A longitudinal passage b located 20 in one side of the nozzle body K maintains communication between the chamber V and the steam inlet R. The longitudinal cylindrical chamber c formed in the tubular extension T concentrically with the ring passage a communicates with a transverse passage d in the nozzle body K and the passage d is open to communication with the inlet E.

The nozzle body K is provided with two 30 longitudinally aligned bores e and f concentric with the chamber c and separated by an upper annular shoulder g. A lower annular shoulder h separates the bore e from the chamber c. The shoulders g and 35 h serve to support and guide an elongated cylindrical tube j having a head k adapted to rest on the shoulder g and extending axially through the bore e, and chamber c beyond the end of the nozzle K and into 40 the diffuser body A terminating at a point approximately in alignment with the narrowest portion of the contracted throat B. The longitudinal bore p of the tube j is adapted to convey water or other liquid, 45 supplied to the bore f from an inlet pipe connection q, to the interior of the diffuser body A. The position of the tube j may be adjusted longitudinally by interposing a spacer between the head k and shoulder g. 50 Live steam entering the nozzle through the steam connection R and passing through the communicating passage b into the annular chamber V and from thence to the ring passage a in the end of the nozzle, is adapted 55 to flow into the throat B and through the diffuser in the form of an envelope as shown at s surrounding the air or vapor, or both, passing from the inlet E into and through the communicating passages d and c, and 60 out of the nozzle around the tube j, as indicated at r. This envelope of steam is itself surrounded by an outer envelope of the same medium which flows through the passages d and c, the outer envelope being formed by 65 the fluid from the inlet E flowing around

the sides of the nozzle within the inlet head G and downwardly past the end of the nozzle between the interior wall of the diffuser body and the envelope of steam as seen at t. The mixture flowing into the throat B thus consists of an outer envelope of air or vapor, 70 surrounding an envelope of steam and an inner envelope of vapor or air from the same source as the vapor or air of the outer ring. The several enveloping strata r, s, t 75 decrease in volume upon entering the throat portion B of the diffuser around the end of the tube j and the pressure increases correspondingly, and approximately at this point a core or jet of cooling water or other liquid w is projected through the center of the vaporous mass. The mixture flowing through the diffuser thus consists of a core of cooling liquid, an inner surrounding envelope of vapor or air, an envelope of steam, 80 and an outer envelope of vapor or air, the mixture being emitted from the enlarged outlet C with all its elements effectively commingled.

The construction of the ring nozzle permits the envelope of steam to present a large area for the entrainment of the air or other vapor, both inside and outside of the steam envelope and the introduction of the cooling liquid at the throat B produces an 85 appreciable condensing effect, all of which tend to the most effective utilization of the principles of pressure augmentation and condensation which are desirable and necessary to obtain the best results with ejectors 100 of the type for which the present invention is adapted.

What we claim is:

1. A jet augmenter or ejector comprising a body portion having an inlet, throat and outlet, a nozzle connected to said body portion and extending into said inlet, a passage in said nozzle communicating with said inlet through which fluid from said inlet is adapted to be drawn, an annular passage in said nozzle surrounding said first mentioned passage adapted to project into said throat an envelope of fluid different from the inlet fluid, said envelope being adapted to be surrounded by an envelope of inlet fluid and a second nozzle in said first mentioned nozzle for supplying to the mixture of previously mentioned fluids a fluid different from either of the other fluids. 115

2. A jet augmenter or ejector comprising a body portion having an inlet, throat and outlet, a nozzle connected to said body portion and extending into said inlet, a passage in said nozzle communicating with said inlet through which air from said inlet is adapted to be drawn, an annular passage in said nozzle surrounding said first mentioned passage adapted to project into said throat an envelope of steam, said steam envelope being adapted to be surrounded by an envelope of 130

air from said inlet and a second nozzle connected to said first mentioned nozzle for supplying a liquid to the mixture of air and steam.

- 5 3. A jet augmenter or ejector comprising a body portion having an inlet, throat and outlet, a nozzle connected to said body portion and extending into said inlet, a longitudinal 15 passage in said nozzle communicating with said inlet through which air is adapted to be drawn from said inlet, an annular passage 20 in said nozzle surrounding said first men-

tioned passage adapted to project into said throat an envelope of steam, said steam envelope being adapted to be surrounded by an envelope of air from said inlet and a second nozzle connected to said first mentioned nozzle and extending into said throat for supplying liquid to the mixture of air and steam.

In testimony whereof we have signed this specification.

PAUL A. BANCEL.
JOHN F. KIRGAN.
